UNITED STATES PATENT OFFICE.

MATTHIAS BROCK, OF ROXBURY, MASSACHUSETTS, ASSIGNOR TO UNITED SHOE MACHINERY COMPANY, OF PATERSON, NEW JERSEY, A CORPORATION OF NEW JERSEY.

LAST.

1,240,174.

Specification of Letters Patent. Patented Sept. 18, 1917.

Application filed August 14, 1912. Serial No. 715,052.

To all whom it may concern:

Be it known that I, MATTHIAS BROCK, a citizen of the United States, residing at Roxbury, in the county of Suffolk and Commonwealth of Massachusetts, have invented certain Improvements in Lasts, of which the following description, in connection with the accompanying drawings, is a specification, like reference characters on the drawings indicating like parts in the several figures.

This invention relates to lasts and particularly to lasts of that type in which the fore and heel parts are movably connected so that the last may be broken to permit it to be inserted in, or removed from a shoe, and may be held in extended condition while in the shoe.

An important feature of the invention is comprised in a simple and efficient lock to hold the last against movement when in extended condition so that relative movement of the parts will be prevented under the usual strains to which the shoe is subjected during the shoe making operations, but which lock may be caused to yield to permit the last to be broken by a simple manipulation.

In the illustrated embodiment of the invention the improved lock is shown applied to a last in which the fore and heel parts are hingedly connected, and the lock is shown as comprising a spring which is fastened at one end to one member of the last and at its opposite, or free end bears yieldingly against the other member and is recurved at said end to engage a curved recess in such member when the last is extended. When the last is broken the free end of the spring is held yieldingly against one of the adjacent surfaces of the last members and thereby serves to frictionally maintain the last in its shortened, or broken condition.

Other features of the invention are comprised in certain important details of construction and combinations of parts which will be hereinafter more particularly described and claimed.

In the drawings:—

50 Figure 1 is a side elevation of a last, with parts broken away, embodying the present invention; and

Fig. 2 is a plan view of the last.

The fore part 2 of the last is shown as 55 having a vertical bore in its bottom to re-

ceive a plug 6, and a vertical, longitudinal saw kerf extends through the lower portion and upwardly a suitable distance in said fore part and to the rear extremity thereof to receive a hinge plate, the forward 60 end of the plate entering a kerf in the plug 6. Said end is pivotally connected to the plug by a pin 10 which is inserted through transverse, alined bores in the fore part and plug. The opposite end of the plate 8 is 65 rigidly secured to the heel part 4 of the last, as by rivets 14 passing through the heel part and plate. The rear extremity or secant end of the fore part is shown as curved at 12 on an arc whose center of curvature is at the hinge pin 10, and the heel part has its forward face curved to agree with the curvature of the surface 12, as shown, so that when the last parts are broken the heel part will swing about the hinge pin 70 10 from the position shown in full lines to that shown in dotted lines in Fig. 1, the adjacent curved surfaces sliding relatively in the direction of their curvature.

The fore part 2 is shown as being cut out 80 in its rear face to provide an inclined groove 16 which is located by the side of the kerf for receiving the plate 8 and progressively increases in depth rearwardly, from its upper to its lower extremity. A locking member, herein shown as a leaf spring 18, and which may be of tempered steel or other suitable material, is secured at its upper end by a screw 18', or other suitable means, in the groove 16 and extends downwardly and 90 rearwardly at an inclination to said groove, the free end of the spring being preferably re-curved or bent as shown at 20. The bent end 20 is designed to be forced by the resilient action of the spring into a curved 95 recess 22, formed in the adjacent forward face of the heel part, when the last is in extended condition, as shown in Fig. 1, and securely locks the last parts in such condition against all of the strains to which the 100 last will be subjected when in a shoe, during the several shoe making operations in connection with which these lasts are intended for use. In the performance of this locking function the curved end 20 of the spring 105 bears firmly against the curved wall of the recess 22 which it engages, and the spring thus acts as an abutment whose resistance to movement of the last parts cannot be overcome until sufficient force is applied to crowd 110

the curved end 20 out of its recess 22, which causes the body of the spring to flex and move forwardly in the recess 16 to the position shown by dotted lines in Fig. 1. Upon

5 continuing the movement of the heel part to break the last the free end of the spring will be held in yielding engagement with that portion of the forward curved surface of the heel part immediately below the recess 22 and will thus act to frictionally hold the last parts in broken condition until a force is exerted sufficient to overcome the frictional resistance offered by the spring when the parts are moved again into ex- 15 tended condition.

Conveniently, the recess 22 to receive the bent end of the locking spring may be formed by boring a hole through the last parts which will be intersected by the line 20 of separation of said parts so that approximately one half of the hole will be formed in each section of the last, as shown in Fig. 2. This construction facilitates the manufacture of these lasts in large quantities.

25 In order to properly limit the movement of the last parts into extended position the hinge plate 8 is provided at its lower edge with a notch 24 which is arranged to engage a suitable stop 26, herein shown as a rivet 30 which passes through the fore part at a point intersecting the lower portion of the kerf which contains the hinge plate 8. The rivet 26 thus in addition to serving as a stop, acts to brace the fore part and holds it 35 against spreading laterally.

From the foregoing it is believed that the operation of the last and the advantages which follow from its use will be apparent without further description. The right is 40 hereby reserved to make such changes in the form, arrangement, and structural details of the several parts as are comprehended by the scope of the following claims.

Having thus described my invention, what 45 I claim as new and desire to secure by Letters Patent of the United States is:—

1. A last comprising a fore part and a heel part movably connected, a spring rigidly secured to one of said parts and extending 50 inwardly of the last substantially parallel to the direction of the relative movement of the fore and heel parts in collapsing and the other part having a recess to be engaged by the free end of the spring, said spring and recess having opposed curved surfaces arranged to resist movement of the last parts when the last is in extended condition.

60 2. A last comprising a fore part and a heel part movably connected, a downwardly extending spring rigidly secured to one of said parts and having its free end upwardly recurved, and the other part having a recess shaped to be engaged by the recurved end 65 of the spring for holding the last in extend-

ed condition, the edge of the recess reacting against the spring substantially in the direction of its radius of curvature at the point of contact.

3. A last comprising a fore part and heel 70 part pivotally connected, a spring having one end rigidly secured to one of said parts, extending toward the other part and having its opposite end recurved, and said other last part having a curved recess arranged in the 75 interior of the last to be engaged by the recurved end of the spring for holding the last in extended condition.

4. A last comprising fore and heel parts 80 movably connected together, a spring secured rigidly to the secant end of one of said parts and having a free end portion extending downwardly and terminating in a reversely curved end abutment and the other part having a curved recess to receive 85 said abutment and coöperating therewith to hold the last in extended condition.

5. A last comprising two parts movably connected, one of said parts being provided with a groove in its secant face and a spring 90 in said groove having its body portion substantially straight and having one end secured to said part and its remaining portion extending downwardly and rearwardly toward the other part and having a recurved 95 end, and the other part having a recess formed with a curved wall to engage said end, the body portion of said spring lying substantially in the line of relative movement of said last parts when the last is ex- 100 tended.

6. A last comprising a fore part having a vertically inclined groove, a spring in said groove having one end secured to said fore part and its remaining portion free, extending rearwardly and terminating in an abutment, and a heel part pivotally connected with said fore part and having a recess to receive said abutment for holding the last in extended condition, said spring being 110 adapted to frictionally engage said heel part outside of said recess for holding the last parts against relative movement when in collapsed condition.

7. A last comprising one part having a 115 groove therein and a spring having one end secured in said groove and extending toward the other part and terminating in a recurved portion, and a second part connected with the first part, said last parts having a curved 120 line of division which forms abutting surfaces in sliding engagement and having also a transverse bore circular in cross section which is intersected by said line of division, a part of said bore forming a recess in one 125 of the last parts for receiving the recurved end of the spring to lock the parts in extended condition.

8. A last comprising one part having a spring rigidly secured thereto at one end 130

and having its opposite end recurved, and a second part hingedly connected with the first part, said parts having a curved line of division which forms abutting surfaces in sliding engagement, said second part having a recess curved to correspond with said recurved end, the parts being so arranged that when the last is extended the spring lies substantially parallel with the line of relative movement of the parts to thereby resist such movement.

9. A last comprising one part having a spring rigidly secured thereto at one end and having its opposite end recurved, and a second part hingedly secured to the first part, said parts having a curved line of di-

vision forming abutting surfaces in sliding contact, said second part having a recess curved to correspond with the recurved end of said spring, said end being adapted to 20 occupy said recess for holding the last extended, and to bear against an adjacent portion of the abutting surface of the second last part for holding the last collapsed.

In testimony whereof I have signed my 25 name to this specification in the presence of two subscribing witnesses.

MATTHIAS BROCK.
